(57) **CLAIM**

The ornamental design for a wind power generator, as shown and described.

DESCRIPTION

FIG. 1 is a perspective view of a wind power generator.

FIG. 2 is a front elevation view thereof.

FIG. 3 is a rear elevation view thereof.

FIG. 4 is a top plan view thereof.

FIG. 5 is a bottom plan view thereof.

FIG. 6 is a left side elevation view thereof.

FIG. 7 is a right side elevation view thereof.

FIG. 8 is an enlarged fragmentary perspective view thereof taken along line 8—8 in FIG. 1.

FIG. 9 is an enlarged fragmentary front view thereof taken along line 9—9 in FIG. 2.

FIG. 10 is an enlarged top plan view thereof; and,

FIG. 11 is an enlarged bottom plan view thereof.

The broken lines shown in the views represent unclaimed subject matter and form no part of the claimed design.
